(57) CLAIM

The ornamental design for a container, as shown and described.

DESCRIPTION

The container of the present invention may be used as a container for liquid water that will subject to freezing or dispensed as ice in small portions. It may also contain objects and be used as an entertainment, decorative or educational article.

FIG. 1 is a perspective view of a container showing our new design;

FIG. 2 is a front elevation view thereof; and,

FIG. 3 is right side elevation view thereof.
